[57] CLAIM

The ornamental design for a tumbler or similar article,
as shown and described.

DESCRIPTION

FIG. 1 is an elevational view of a tumbler or similar
article showing my new design in the size and propor-
tions of a cocktail glass;

FIG. 2 is a bottom plan view thereof;

FIG. 3 is a top perspective view thereof;
FIG. 4 is an elevational view of a tumbler or similar
article showing my new design in the size and propor-
tions of a juice glass;

FIG. 5 is a bottom plan view of FIG. 4;

FIG. 6 is an elevational view of a tumbler or similar
article showing my new design in the size and propor-
tions of a water glass; and

FIG. 7 is a bottom plan view of FIG. 6.
